UNITED STATES PATENT OFFICE.

JOHN TOMASZEWSKI, OF WARREN, RHODE ISLAND.

CONVERTIBLE BED, CHAIR, AND TABLE.

1,259,932.

Specification of Letters Patent.

Patented Mar. 19, 1918.

Application filed March 9, 1917. Serial No. 153,654.

To all whom it may concern:

Be it known that I, JOHN TOMASZEWSKI, a subject of the Emperor of Austria, resident of Warren, county of Bristol, and State of Rhode Island, have invented certain new and useful Improvements in Convertible Beds, Chairs, and Tables, of which the following is a specification.

This invention relates to improvements in household furniture, and has as its principal object the provision of an article which may be used without modification by properly manipulating the parts, either as a bed, a table or a chair.

15 This object is attained by the novel design, construction and combination of parts hereafter described and shown in the accompanying drawings, forming a material part of this specification, and in which:

20 Figure 1 is a top plan view of the article as extended in condition to be used as a bed.

Fig. 2 is a side elevational view of the same.

25 Fig. 3 is a side view of the same article when folded to be used as a table.

Fig. 4 is a fragmental perspective view of the same when extended as a bed.

Fig. 5 is a perspective view of a part of the same as when used as a chair.

30 Fig. 6 is a perspective view showing the device when used as a table, one of the leaves being raised, and

Fig. 7 is a perspective view showing one of the joint constructions.

35 The invention is comprised of two pairs of similarly formed legs 10 connected together by a bar 11 and having rigidly extending lateral arms 12 between which are secured slats 14, one pair of the arms 12 having downwardly extending projections 15 containing a transverse recess or slot 16 adapted to act in the manner of a socket receptive of a corresponding projection 18 formed with the corresponding projection 19 from the other pair of arms.

Both ends of each pair of arms 12 have vertical slots 20 in which are engaged foldable leg elements 21 by means of the pins 22 passing through holes 22' at the end of the arms 12 in the manner of a hinge, a portion of the leg elements being of reduced thickness, as at 23, and adapted to engage with corresponding extensions from the oppositely hinged arm, both of the reduced portions being held when extended in the form of a bed as shown in Fig. 1 by means of pins

24, the same passing through holes formed transversely through the reduced portion.

In order to further strengthen the device when extended as to be used for a bed, as 60 shown in Figs. 1 and 4, the removable element 25 is held closely against the lower side of the elements 21 and 23 by means of hooks 27 so as to form a rigid structure, other slats 28 being disposed from one to the other. 65

These hook elements, which are pivoted at 29 are also used to engage with pins 30 set in the outer side of the projection 15 so that when it is desired to use the article as a chair the legs may be extended vertically, substantially parallel with the legs 10 and the hook engaged with the pin 30, holding the same in a rigid position. 70

As shown in Fig. 5, the chair may be used by applying a cushion, the opposite member 75 being used for a like purpose.

When it is desired to use the article as a table, as shown in Figs. 3 and 6, the two front legs 21 are placed closely adjacent; the projection 18 extending directly into the 80 recess 16, the extending arm elements 12 being clamped together by hooks 38 disposed upon their inner side.

In this condition, the plate or cover elements 35 which are secured by hinges 36 to 85 the upper part of the legs 10 are folded over, forming in effect a level and substantial table top, as can best be seen in Fig. 3.

When used as a chair, the top is extended as shown in Fig. 5, forming a back for the 90 chair, and also in an extended position, as shown in Figs. 1, 2, and 4, when the article is used as a bed, the plate 31 being held in a vertical position by means of the hooks 37.

From the foregoing, it will be seen that a 95 substantial structure has been described and shown capable of being put into the several uses herein explained, and that the changes from one to another may be readily made without recourse to the use of tools of any 100 kind whatever.

Having thus described my invention, what I claim as new, and desire to secure by Letters Patent, is:—

1. In a structure of the class described, 105 the combination with two pairs of outer legs, connecting means for holding said legs rigidly apart, a pair of arms extending laterally from said legs at right angles to said connecting means, pairs of inner legs 110 pivotally engaged with said extending arms at the outer ends thereof adapted to be

folded downward or extended horizontally at will, means for engaging said pairs of inner legs together when extended, means for supporting transverse slats combined with said arms and inner legs, and a pair of cover plates hinged to the upper portion of said outer legs, said cover plates being adapted to be positioned either vertically or horizontally.

2. In a structure of the class described, the combination with two pairs of outer rigidly supported legs, arms extending laterally from said legs, means combined with said arms whereby they may be engaged together, two pairs of inner legs hingedly engaged with said arms, means for holding said inner legs extended horizontally or folded vertically, and a pair of cover plates adapted to be extended horizontally or vertically at will.

3. In a structure of the class described, the combination with two pairs of outer legs, a

rigid brace between each pair, a pair of arms extending laterally from said legs, projections formed on the lower side of said arms, 25 one of said projections containing a recess, corresponding lugs formed on the other projections enterable in the mentioned recesses, inner legs hingedly secured in said arms, said inner legs being adapted to be engaged 30 together, means for holding said inner legs in an extended horizontal position, means for holding said inner legs extended vertically, a plurality of slats removably engaged with said arms and legs when extended, a sectional cover hinged to the edges of the upper ends of said outer legs, means for holding said sectional covers in an erect position, and means for reinforcing said inner legs when in an extended position. 40

In testimony whereof I have affixed my signature this 24th day of February, 1917.

JOHN TOMASZEWSKI.
